F. J. MATCHETTE & R. RADDATZ.
VACUUM CLEANING AND HEATING SYSTEM.
APPLICATION FILED SEPT. 30, 1910.

1,106,349.

Patented Aug. 4, 1914

UNITED STATES PATENT OFFICE.

FRANK J. MATCHETTE AND RICHARD RADDATZ, OF MILWAUKEE, WISCONSIN, ASSIGNEES, BY MESNE ASSIGNMENTS, TO RICHMOND RADIATOR COMPANY, OF NEW YORK, N. Y., A CORPORATION OF DELAWARE.

VACUUM CLEANING AND HEATING SYSTEM.

1,106,349.

Specification of Letters Patent.

Patented Aug. 4, 1914.

Original application filed March 2, 1905, Serial No. 248,106. Divided and this application filed September 30, 1910. Serial No. 584,587.

To all whom it may concern:

Be it known that we, FRANK J. MATCHETTE and RICHARD RADDATZ, citizens of the United States, residing at Milwaukee, in the county 5 of Milwaukee and State of Wisconsin, have invented certain new and useful Improvements in Vacuum Cleaning and Heating Systems, of which the following is a specification, reference being had to the accompanying drawing, forming a part thereof.

This invention relates to apparatus designed to remove dust and dirt from floors, walls or other surfaces and from carpets, furniture or the like, by means of a current 15 of air.

The main object of the present invention is to utilize the exhaust steam or other heating medium from the vacuum producing means of the cleaning system for other purposes, such as supplying heat for the operation of feed water heaters, radiators and the like.

It consists in the construction, arrangement and combination of parts as hereinabove particularly described and pointed out in the claims.

The drawing shows partly in elevation and partly in section, apparatus embodying the invention.

30 The apparatus comprises a system of piping represented in the present case by a suction or service main *a*, and one or more branches *b*, having on the several floors or in different apartments of the buildings in 35 which the apparatus is installed, service inlet connections *c*, provided with valves, for the attachment of tools or cleaners (not shown).

40 A stationary steam boiler *d*, usually located in the basement of the building, is shown as provided with a smoke stack *e* and as mounted in an ordinary brick setting which forms a furnace with a combustion chamber *f* above and an ash pit *g* below a 45 grate *h*.

45 The apparatus is preferably provided with a primary dust collector or separator *i*, into which the suction or service main *a* discharges for removing the heavier and 50 coarser refuse or dirt from the air with which it is taken up by the cleaning tools. This dust collector or separator, which is preferably located in the basement of the

building or near the furnace, is connected with a secondary dust collector or separator 55 *j*, by a pipe *k*, and serves to prevent the coarser refuse or dirt drawn with air into the apparatus from passing on to and clogging or interfering with the operation of an aspirator or ejector *l* in the pipe *k*. A 60 pipe *m* connects the aspirator *l* with the boiler *d* or with a steam supply pipe *n* leading therefrom. The pipe *m* is provided with a valve *o* for manually shutting off steam from the aspirator and also with an 65 automatic regulating valve *p* operated by a diaphragm or the like, indicated at *q*, and connected on one side by a pipe *r* with the pipe *k* on the inlet side of the aspirator, or with any convenient part of the apparatus 70 in which vacuum is maintained, the valve *p* and its actuating device *q*, with their connections, constituting an automatic controller or regulator governing the supply of steam to the aspirator and the operation of 75 the aspirator in accordance with the varying demands upon the apparatus and consequent variations of vacuum or service pressure within the system of piping.

80 A pipe *s* provided with a valve *t* connects the lower part of the secondary dust collector *j* with the combustion chamber *f* of the furnace above the grate *h*, and a pipe *u* provided with a valve *v* connects the upper part of said collector or separator with a 85 three-way valve *w*, one branch of which is connected with a blast nozzle *x* in the smoke stack *e*, while the other branch is connected with a blast nozzle *y* in a ventilating flue, waste conduit or other duct *z*. Another pipe 90 2, provided with a valve 3, connects said dust collector or separator *j* at a point above which dust and dirt are allowed to accumulate therein, with a three-way valve 4, one branch of which is connected by a pipe 5 95 with the ash pit *g* of the furnace below the grate *h*, while the other branch is connected by a pipe 6 with a feed water heater or other heating device, represented by a radiator 7.

100 The apparatus as herein shown and described may be operated in several ways. In case it is desired to discharge the exhaust from the aspirator *l* directly into the furnace, the valves *v* and 3 are closed and the valve *t* is opened, and thereupon the 105 mingled air, steam and dust delivered from

the aspirator into the dust collector *j* are directed through the pipe *s* into the combustion chamber *f*, thereby increasing the draft of the furnace and aiding the combustion of fuel therein, besides disposing in a convenient, harmless and inoffensive manner, of the fine dust and dirt which are not removed by the primary separator *i*.

By closing the valve *t* and opening the valve *v*, the exhaust steam and air from which the dust is removed in the collector or separator *j*, may be discharged according to the position of the three-way valve *w* from the blast nozzle *x* in the smoke stack *e*, thereby increasing the draft of the furnace, or from the blast nozzle *y* in the flue or duct *z*, thereby producing a draft in said flue or duct.

By closing the valves *s* and *v* and opening the valve *z*, the exhaust steam and air may, according to the position of the three-way valve *4*, be discharged through the pipe *5* into the ash pit of the furnace, thereby tending to keep the grate bars cool and to soften clinkers, as well as operating to increase the draft of the furnace and aid combustion, or it may be discharged through the pipe *6* into the radiator or other heating device *7*, whereby the heat of the steam is utilized to advantage without affecting the operation or impairing the efficiency of the cleaning apparatus.

During the operation of the apparatus in the various ways last described, when the exhaust steam and air are directed into the smoke stack *e*, duct *z*, ash pit *g* or heater *7*, the dust accumulating in the collector or separator *j*, is discharged from time to time into the furnace by opening the valve *t*.

Various changes in the construction and arrangement of the several parts of the apparatus may be made without departing from the principle and scope of the invention.

Features shown and not claimed herein are claimed in my co-pending applications Serial Numbers 584,585 and 584,586.

We claim:

1. In a vacuum cleaning and heating system, a piping-system having means for attachment to a vacuum cleaner, a steam as-

pirator in communication with a pressure supply and adapted to draw air and dust therethrough, a dust-collector or separator in said system, means for supplying steam to said aspirator for operating the same, and a heating-system connected with the exhaust of said aspirator, said system being provided with valves controlling points of disposition of the exhaust from the aspirator. 60

2. In a vacuum cleaning and heating system, in combination, a piping-system having means for attachment to a vacuum cleaner, a steam aspirator in communication with a pressure supply and adapted to draw air and dust through the system and to maintain a vacuum therein, means for supplying steam to said aspirator, a dust-collector in the exhaust of said aspirator and provided with a collecting receptacle, said collector having a dust discharge in the collecting receptacle thereof, whereby the collected dust is blown out of the collector on opening said discharge, and a heater connected with said collector at a point above which dust and dirt accumulate therein and receiving the purified air and steam therefrom. 70

3. In a vacuum cleaning and heating system, in combination, a piping-system having means for attachment to a vacuum cleaner, a steam aspirator in communication with a pressure supply and adapted to draw air and dust through said system and maintain a vacuum therein, a steam-generator, including a furnace, adapted to supply steam to said aspirator to operate it, a heater receiving the exhaust of said aspirator, a dust-collector interposed between said aspirator and said heater and having the heater connected therewith at a point above which dust and dirt accumulate in the collector, and a discharge for said dust-collector arranged to discharge the dust collected therein into said furnace. 80

In witness whereof we hereto affix our signatures in presence of two witnesses.

FRANK J. MATCHETTE.
RICHARD RADDATZ.
